UNITED STATES PATENT OFFICE

2,575,421

AUTOGRAPHIC REGISTER

Frederick Edward Lanegan, London, England,
assignor to W. H. Smith & Son Limited, London, England, a British company

Application August 22, 1946, Serial No. 692,303
In Great Britain December 28, 1944

1 Claim. (Cl. 282—16)

1

This invention relates to so-called autographic registers of the type comprising a container providing a compartment for a supply of continuous stationery in the form of a zig-zag pack, a writing tablet over which the stationery may be drawn (with any convenient arrangement of interleaved transfer material) and beyond which it may be ejected from the register. In registers of this type means are provided for traversing the stationery past the writing tablet usually through the medium of an external handle so arranged that on each rotation or partial rotation the stationery is traversed one form length through the machine.

In an autographic register of the type described—for use in particular in businesses such as laundries and dry-cleaning establishments—it has already been proposed to enclose within the container a reel of numbered identification tape and to drive this tape through the interior of the container in alignment with the stationery so that at each delivery a length of tape corresponding to or appropriate to the form length of the stationery is ejected.

This invention is likewise concerned with the provision of means for delivering a tape in company with the stationery by means of the mechanism employed for driving the stationery strips.

The invention provides an autographic register of the type described which is characterised by the provision of means for supporting a supply of identification tape and a pin-wheel driven in synchronism with the stationery-traversing means and arranged to make feeding engagement with perforations in the tape to issue the tape from the register in synchronism with the ejection of the stationery from the register.

In the preferred form of the register the stationery traversing means include one or more pin-wheels carried on a driving spindle and arranged to make feeding engagement with perforations in the stationery and the tape-feeding pin-wheel is also carried on the spindle for rotation therewith. If desired, the tape-feeding pin-wheel may be of different diameter from that of the stationery feeding wheel or wheels so that the length of tape fed at each operation of the external operating handle or the equivalent is different from the length of stationery so fed.

Conveniently the register includes a guillotine, which may be operated automatically, for cutting off the tape issued.

One specific register according to the invention will now be described by way of example and with reference to the accompanying drawings, in which:

2

Figure 1 is an elevation showing the provision of the identification tape-feeding means in a register of known type;

Figure 2 is a plan of part of the register shown in Figure 1;

Figure 3 illustrates a length of the tape as fed at each operation of the register, and

Figure 4 is an enlarged detail view of the mechanism for operating the clamping bar and the guillotine.

The register forming the subject of this example is of the type in which a zigzag pack of continuous stationery 100 is received in a compartment of the register and is traversed step-by-step over a writing plate 101 by means of pin-wheel 14 rotatable on a shaft 13. The stationery is finally ejected from the register and torn off into form lengths.

In this example of the invention the following arrangement is adopted. The identification tape 1 is wound on a bobbin 2 freely mounted for rotation on a spindle 3. The spindle 3 is carried in a sleeve 4 fixed to an arm 5 pivoted at 6 to the side 7 of a frame located inside the register casing 8. Friction discs 9 are carried on the spindle 3 and are pressed against the sides of the tape by a spring 10. The sleeve 4 is received within a slot, not shown, in the side 7. When it is desired to replenish the tape the top of the register is opened and the spindle carrying the bobbin is raised by pivotal movement of the arm 5 about the pivot 6. The C-washer 11 is removed from the end of the spindle 3 which allows the spindle to be removed and replaced by a new bobbin and the parts re-assembled.

The tape is taken from the bobbin 2 over the top of a pin-wheel 12 mounted on a spindle 13 for rotation therewith. The spindle 13 also carries a pair of stationery feeding pin-wheels 14, of which only one is shown in the drawings. The pin-wheels 14 are arranged to engage with marginal apertures provided in the stationery strips. In this example, the tape-feeding pin-wheel 12 has twelve pins and the stationery feeding pin-wheels have thirteen pins, resulting in a slightly greater feed of stationery than tape at each feed operation. The pin-wheels in each case have fixed pins, but they may, if desired, be provided with movable pins arranged as described in British Patent Specification No. 408,125. In the register to which this example is applied the spindle 13 makes one revolution for each operation of the handle. The length of tape issued at each operation is illustrated in Figure 3 which shows the tape divided into three sections arranged for

separation after issue for attachment to garments or other articles so as to identify them with the information contained on the form or other stationery issued simultaneously with the tape.

After the tape has passed over the pin-wheel 12 it is led between the blades 15 and 16 of a guillotine arranged to cut off each length of tape as it issues. The movable blade 15 of the guillotine is operated automatically in the following way. The register is provided, in known manner, with a clamping bar 17 for clamping the stationery during the writing operation the bar being carried by arms 33 pivotally supported at 34 and the bar being automatically raised to release the stationery during the operation of traversing the stationery and lowered at the end of the traversing operation to clamp the stationery against the top of the register. The movements of this clamping bar are employed, in accordance with the invention, to operate the guillotine. For this purpose, the spindle 18 carrying the blade 15 is provided with an arm 19 of which the free end extends under a projection on the clamping bar. The arm 19 is urged upwardly by a spring 20 acting through a plunger 21 in contact with the arm. When the clamping bar 17 is raised to release the stationery, the arm 19 is allowed to rise under the influence of the spring 20 and the blade 15 is thereby lifted clear of the stationary blade 16 which allows the tape to be fed between the two blades. At the end of the operation of feeding the stationery and the tape the clamping bar 17 is lowered, by spring action, and presses down the arm 19 which in turn lowers the blade 15 and cuts off the length of tape issued.

In the register described in the above example the pin-wheel spindle 13 makes one revolution for each operation of the handle and the lifting and falling movement of the clamping bar is conveniently arranged by means of a follower 30 co-operating with a flange 31 provided on one of the stationary feeding pin-wheels and having a depression 32 into which the follower drops when the clamping bar is to be lowered. In cases in which the pin-wheel spindle makes more than one revolution at each operation of the handle, the clamping bar may be operated by means of a cam formed on the handle shaft instead of on the pin-wheel spindle. Alternatively, the clamping bar may be operated from the stop pawl in the arrangement described in British Patent Application No. 35111/45 dated December 28, 1945.

In an autographic register of the type described it is customary, in many cases, to provide a locked compartment in which one or more of the copy records, after inscription, is delivered as a continuous strip and so retained in the register. A similar arrangement may be adopted in an appa-

ratus embodying the present invention, but the invention is not restricted to the provision of such an arrangement.

I claim:

5 An autographic register comprising as an operative combination, a container for a supply of continuous stationery, a writing platen over a portion of the container, two pin-wheel feeding devices for engagement in marginal perforations in the stationery, and rotatable step-by-step between writing operations on the stationery to traverse the stationery over the platen and to feed the stationery to a station at which it is ejected from the register, means for supporting in relation to the container a supply of identification tape, a tape-feeding pin-wheel arranged to make feeding engagement with perforations in the tape and on rotation to draw the tape from the supply and to feed it to an ejection station, means for driving the tape-feeding and the stationery-feeding pin-wheels step-by-step in synchronism to issue tape from the register and at the same time to eject stationery from the register, means for constraining the stationery and the tape to follow separated paths in the register, a clamping bar for clamping the stationery against the top of the container during writing operations, means operable by rotation of the stationery-feeding pin-wheels for automatically lifting the bar to release the stationery during the operation of traversing the stationery and then to lower the bar, a guillotine for cutting off the identification tape ejected from the register, and a lever pivotally supported in relation to the container and platen carrying at the end of one arm the guillotine and cooperating at the end of the other arm with the clamping bar in manner such that as the bar is lowered to clamp the stationery the lever is rocked to lower the guillotine and thereby to cut off the ejected tape.

FREDERICK EDWARD LANEGAN.
